5 Claims. (Cl. 179—171)

This invention relates to electrical signal amplifiers, and more particularly to high gain amplifiers, the principal object of the invention being to provide a novel device of this class by which materially increased gain and other desirable results may be obtained. The invention is directed particularly to high-gain amplifiers in which either or both of the input and output circuits comprise resonant circuits adapted to transmit wave signals of certain frequencies and to attenuate signals of other frequencies. The invention may be employed, for example, in the intermediate frequency amplifier of a superheterodyne radio receiver, and for convenience it will be described with reference to such use, but it will be understood that the invention is not limited thereto and is capable of use in any instance where a high-gain amplifier may be desired.

The invention is also particularly adapted for use with vacuum tube amplifiers of the pentode type, which are characterized by having at least two electrodes positioned between the control electrode and the output electrode, one of the said intermediate electrodes being so biased with respect to the cathode that it draws no space current.

Another object of the invention is to provide a high-gain amplifier stage including a vacuum tube having a high amplification factor and tuned input and output circuits, which stage is characterized by stability of operation and unusually high gain.

Still another object of the invention is to provide a tuned input and output circuit arrangement for an amplifier of the pentode type, by which an amplifier stage having band-pass filter characteristics may be obtained, and in which the attenuation of signals of undesired frequency is symmetrical with respect to a mean frequency.

A further object of the invention is to provide an input circuit for a pentode amplifier so constructed and arranged that the dynamic input admittance of the amplifier may be made substantially zero regardless of the nature of its output circuit, thereby eliminating certain defects or objectionable characteristics of the amplifier.

Still another object of the invention is to provide a simple and economical circuit for a high-gain tuned amplifier by which the amplifier may be stabilized.

As above indicated, a principal purpose of the present invention is to obviate certain objectionable characteristics of an amplifier caused by its dynamic input impedance. As is well known in the art, the input admittance of a vacuum tube

amplifier having some sort of a load circuit, may be divided into two parts. One of these parts, which may be designated the static admittance, is determined by the physical dimensions of the tube elements and is the admittance which would be measured when the tube is deenergized. The second part, or dynamic admittance, is that part of the admittance which is determined by the flow of energy between the control grid and other elements of the tube and will, in general, depend upon the nature of the output circuit, the gain or amplification of the tube, and the inter-electrode capacities between the control grid and several other elements of the tube. In the usual operation of a pentode amplifier, in which the screen grid and the suppressor grid are effectively connected to the cathode as far as alternating currents are concerned, and in which the anode is connected to a load circuit, the dynamic admittance will have the nature of a capacitance in shunt with a resistance. Where the output circuit has an inductive component, the conductance or real part of the dynamic admittance, i. e. that part of the admittance due to the shunt resistance will be negative and will correspond to a negative shunt resistance; while for a capacitive load, the conductance or real part of the dynamic admittance will be positive. The resistive component of the load will, in general, reflect back and appear as a positive susceptance or as an effective shunt capacitive element. If the input circuit for the tube is a parallel tuned circuit, it will be apparent that the dynamic admittance of the tube, which is effectively in shunt with the tuned input circuit and adds to the admittance thereof, will appreciably modify the characteristics of the whole circuit. For example, if the equivalent conductance of the tuned input circuit is less in absolute magnitude than the negative conductance of the dynamic admittance when the output circuit is inductive, the tube will oscillate of its own accord. Under less extreme conditions, the filter characteristics of the input circuit will be appreciably distorted. The present invention provides a simple and economical method by which the dynamic admittance of an amplifier may be reduced substantially to zero, thereby eliminating the above defects or objectionable characteristics.

The invention may be more fully understood by reference to the accompanying drawings and the following detailed description.

In the drawings:

Fig. 1 is a diagrammatic illustration of a tuned

high-gain amplifier stage employing a preferred embodiment of the invention;

Fig. 2 represents the equivalent circuit of Fig. 1 rearranged in the form of a bridge circuit, by which a clear understanding of the operation of the circuit may be had, and in which the principal portion and elements of the circuit are shown by the heavy lines, while the less important portion and elements of the circuit are shown by 10 lighter lines; and

Fig. 3 illustrates certain dynamic characteristics of the amplifier stage for several degrees of unbalance.

Referring now to Fig. 1, the amplifier stage 15 may comprise a tuned input circuit including a transformer T_1 , a tuned output circuit including a transformer T_2 , and a vacuum tube amplifier V of the pentode type. The transformer T_1 may include a primary winding L_1 shunted by 20 a condenser C_1 to form a tuned input circuit for the stage. The secondary winding L_2 of the transformer may also be shunted by a condenser C_2 to form another tuned circuit, which constitutes the input circuit for the tube V and is 25 connected to the control grid, and through a blocking condenser C_b to the cathode of the tube. In accordance with the invention, a tertiary winding L_3 is connected to ground and to the suppressor grid of tube V for purposes which 30 will be described in detail hereinafter. L_1 and L_3 are inductively coupled to L_2 but L_1 need not be directly coupled to L_3 . The anode of the tube V may be connected to a source of electrical energy B through the primary winding L_4 of the 35 transformer T_2 , which winding may be shunted by a condenser C_4 to form a tuned output circuit for the tube. The output signal of the stage may be obtained from the secondary winding L_5 of the transformer T_2 , which secondary 40 winding may be shunted by a condenser C_5 to form a tuned output circuit. A biasing voltage may be applied to the control grid of the tube V by means of the isolating resistance R and the blocking condenser C_b , which condenser will 45 have a negligible impedance for signals of the frequency which it is desired to transmit. The screen grid of the tube may be supplied with energy by means of the source B , which may also supply the anode, as above noted.

50 For convenience, it may be considered that the amplifier stage constitutes part of an intermediate frequency amplifier of a superheterodyne radio receiver and that it is designed to transmit wave signals in a certain fixed frequency band and to attenuate wave signals of other frequencies. In these circumstances, the primary and secondary windings of transformers T_1 and T_2 would all be tuned to substantially the same frequency, and the coupling between the primary 55 and secondary windings of each transformer might approximate critical coupling. It will be understood, however, that it is not necessary that the input and output circuits be of this nature. For example, the invention is well adapted for use in amplifiers of the radio frequency type, in which case the input transformer might comprise an untuned primary winding and a broadly resonant secondary winding adapted to transmit signals over a wide frequency band, and 60 the output circuit might comprise any conventional load circuit.

To facilitate the following description, the electrodes of the vacuum tube V other than the cathode K , may be designated g_1 , g_2 , g_3 and g_4 65 in order of their spacing from the cathode fol-

lowing the conventional practice. Thus the control grid is g_1 , the screen is g_2 , the suppressor grid is g_3 , and the anode is g_4 . Certain inter-electrode capacitances, that is capacitances between groups of two of these elements and their associated leads, are of importance and these capacitances may be designated by means of a double subscript. Thus, for example, C_{14} will designate the inter-electrode capacitance between the elements g_1 and g_4 . The capacitance 10 between any of the said electrodes and the cathode will be designated by the subscript zero and the number of the electrode. Thus, the capacitance between the control grid and cathode may be C_{01} . 15

Considering for the moment the conventional operation of the device which would take place in the absence of the tertiary winding L_3 and if g_3 were connected to ground, it will be observed that the signal between g_4 and the cathode K or ground which may be designated E_p , will be dependent upon the signal between g_1 and ground, which may be designated E_{g1} , and in general the former signal will be of considerably greater magnitude than the latter. If the load 20 circuit for g_4 were purely resistive, the signal E_p would be exactly opposite in phase, that is 180° out of phase, with respect to the signal E_{g1} and of considerably greater magnitude. For example, the signal E_p might be 100 times the signal 30 E_{g1} . Due to the fact that there will inevitably be some slight capacity C_{14} between g_1 and g_4 , signal energy will be transferred between g_1 and g_4 . In the particular instance, this effect might be represented by introducing an additional equivalent capacity between g_1 and ground having a value proportional to C_{14} multiplied by the voltage ratio between E_p and E_{g1} . Thus, in the particular instance above noted, this effective capacity would be 100 times as great as C_{14} . 40

If, now, the load circuit contains an inductive component, the voltage E_p will be displaced from E_{g1} by an amount greater than 180° . This voltage may be represented by two components one 180° and the other 270° out of phase with respect to E_{g1} . That part of the voltage E_p which is 270° out of phase with respect to E_{g1} will effectively introduce a negative conductance between g_1 and ground, since it will cause energy to be transferred from the output circuit to the 50 input circuit. If on the other hand, the output circuit contained a capacitive component, then the voltage E_p would be out of phase with respect to E_{g1} by less than 180° , and that part which was 90° out of phase would reflect back as an 55 equivalent positive conductance between g_1 and ground, since under such conductances, energy would be transferred from the input circuit to the output circuit. In both cases, that component of the voltage E_p which is 180° out of phase with respect to E_{g1} will reflect back as an augmented capacitance or positive susceptance. 60

By means of the present invention, the input circuit for the amplifier may be so arranged that the control voltage E_{g1} is independent of the voltage E_p , and hence no energy will be transferred from the output circuit to the input circuit or vice versa, except through the thermionic operation of the vacuum tube, and the input admittance of the tube will be independent of the 70 nature of the output circuit. The manner in which the invention, as embodied in Fig. 1, accomplishes these results may be more clearly understood by reference to Fig. 2, wherein the circuit of Fig. 1 has been replaced by an equiv- 75

alent bridge circuit. The four corners of the bridge, which represent points of different potential in the vacuum tube V, considered in a clockwise direction are, g_1 , g_4 , g_3 and $K-g_2$. The last point corresponds to the potential of the cathode and that of the screen grid g_2 . While these two elements are at different D. C. potentials, with respect to alternating currents of the frequency which the amplifier is adapted to transmit, the 10 two are at the same potential. The bridge arm between the points $K-g_2$ and g_1 includes the input circuit and of this it is necessary to show only the secondary L_2 which, of course, is shunted by the condenser C_2 and the tube capacitance C_{01} . 15 This latter capacitance will, of course, include the capacitance C_{12} but since for A. C. components, the cathode and g_2 are at the same potential, hereinafter it will be understood that any capacitance between a grid and the cathode will 20 include the capacitance between that grid and g_2 . The bridge arm between $K-g_2$ and g_3 will include the tertiary winding L_3 which, of course, will be shunted by the less important tube capacity C_{03} . The diagonal of the bridge between $K-g_2$ 25 and g_4 will include the output circuit, of which it is necessary to show only the tuned primary L_4 shunted by an equivalent voltage ($-\mu E_{g1}$) in series with an equivalent resistance R_p . The representation here is the conventional equivalent 30 form for a vacuum tube, by which the vacuum tube is represented by a generated voltage equal in magnitude but opposite in phase with respect to the voltage between the control grid and cathode multiplied by the amplification factor of the 35 tube, and a series resistance R_p , which represents the equivalent anode-to-cathode dynamic resistance of the tube. Thus, the voltage between the diagonal points $K-g_2$ and g_4 will represent the A. C. voltage between g_4 and the cathode. 40 The bridge arm between g_1 and g_4 will include inter-electrode capacitance C_{14} , while the arm between g_3 and g_4 will include the inter-electrode capacitance C_{34} . The diagonal between g_1 and g_3 45 will include the tube capacitance C_{13} , which is of little importance.

It is characteristic of a bridge such as that shown, that if the voltage ratios between two diagonally opposite points, such as points g_1 and g_3 , and another point, such as $K-g_2$ are proportional respectively to the two reactances between the said diagonally opposite points and the fourth point (g_4) of the bridge, then the bridge is so balanced that any voltage between the fourth point g_4 and the said diagonally opposite points 55 $K-g_2$ can have no effect whatsoever upon the voltage between the other two diagonally opposite points (g_1 and g_3). This condition is obtained, following the practice of the invention, by coupling L_2 and L_3 so that any voltage across L_2 such as E_g will cause a corresponding voltage 60 between $K-g_2$ and g_3 , the latter voltage being designated E_{g3} . Thus, the impedances in the two arms of the bridge $K-g_2$ to g_1 and $K-g_2$ to g_3 may be replaced by the voltage dividing network shown in broken-line representation designated VD , the function of which is to arrange the voltage between $K-g_2$ and g_3 , that is E_{g3} , so that it is at all times proportional to and opposite in phase with the voltage between $K-g_2$ and g_1 , that 65 is E_{g1} .

Considering for the moment the other two arms of the bridge, the capacitance C_{14} will be very small due to the fact that the control grid g_1 is almost completely shielded from g_4 by means of the screen grid g_2 . For example, in a commercial

vacuum tube of the pentode type which might be used, this capacitance might amount to a few thousandths of a micro-micro-farad. On the other hand, the capacitance C_{34} will be relatively large, as compared with C_{14} , due to the fact that g_3 and g_4 are closely adjacent one another and to the further fact that in general tube practice the leads to these elements are brought out of the same end of the tube envelope, whereas the lead to g_1 is taken out at the opposite end. For example, in a commercial tube such as previously mentioned, the capacitance C_{34} may amount to several micro-micro-farads. Thus the impedance between g_1 and g_4 may be several hundred times as large as that between g_3 and g_4 . For example, in the particular case mentioned the ratio would be around 500 or 1000 to 1. Thus, it will be seen it is only necessary to provide a very small voltage E_{g3} between $K-g_2$ and g_3 as compared with the voltage E_{g1} between $K-g_2$ and g_1 to obtain the desired balanced condition of the bridge. In the above example, E_{g3} would be between $\frac{1}{10}$ and $\frac{1}{5}$ of 1% of E_{g1} . This voltage E_{g3} may easily be obtained by providing the tertiary winding L_3 coupled to the secondary winding L_2 by a mutual inductance M_{23} . As will be apparent, the necessary condition for balance is that the ratio of L_2 to M_{23} should be equal to the ratio of C_{34} to C_{14} , that is

$$\frac{L_2}{M_{23}} = \frac{C_{34}}{C_{14}}$$

30

It follows that the ratio of E_{g1} to E_{g3} equals the ratio of C_{34} to C_{14} , that is

$$\frac{E_{g1}}{E_{g3}} = \frac{C_{34}}{C_{14}}$$

35

While from a theoretical point of view it is desirable that the coefficient of coupling between L_2 and L_3 be unity in order to obtain perfect balance for all frequencies, for practical purposes this condition is not necessary, and while the coefficient of coupling between the two should preferably be as large as possible, satisfactory stabilization may be obtained even for input and output circuits having a very high LC ratio when this coefficient of coupling is as small as 5 or 10%, provided the above relation holds true.

As will be apparent, it is highly desirable that the tube capacitance C_{34} should be considerably larger than C_{14} and for this reason it is preferable that the tube V should include a screening element g_2 which serves to screen g_1 from g_4 and thus to minimize the value C_{14} . The use of such an element is also desirable in that it markedly increases the gain or amplification factor of the tube. Such increase in amplification, however, in the absence of the present invention, would limit the impedance of the load circuit that could be employed, which, in turn, would tend to limit the useful stage gain. By using the circuit of the present invention, these objections are overcome and it is possible to obtain optimum efficient operation of the stage. In the practice of the invention, the presence of g_2 is further desirable in that by minimizing C_{14} , and thus increasing the ratio of C_{34} to C_{14} , it minimizes the magnitude of the voltage to be applied to g_3 and thus minimizes the effect of g_3 in controlling the space current to the plate. It will be seen that since g_1 , g_2 and g_3 are all interposed between the cathode and g_4 , each will have an effect upon the thermionic or space current in the tube, which current should be distinguished from the current flow due to the inter-electrode capacitance of the tube. As far as the space current per se is

40

45

50

55

60

65

70

75

concerned, g_1 will have the greatest control over it, g_2 a lesser control, and g_3 an even smaller control. Since the voltage applied to g_3 is considerably less than that applied to g_1 in the preferred 5 form of the invention and since g_3 has a smaller effect upon the space current than g_1 , for practical purposes, the effect of g_3 may be neglected. It will be noted, however, that the voltage of g_3 is opposite in phase to that of g_1 and would tend 10 to reduce the gain of the stage, were it not for the presence of g_2 which renders the actual effect of g_3 on the space current negligibly small. In the above example the control exerted by g_3 might amount to $\frac{1}{100}$ or $\frac{1}{100}$ of 1% of that due to g_1 . 15 It is preferable that g_3 be so biased as to draw no space current. This may be accomplished by conductively connecting g_3 to ground, as illustrated. The balance obtained in the bridge of Fig. 2 is predicated upon the hypothesis that none 20 of the arms of the bridge conduct space current, and it will be apparent that if g_3 , for example, were so biased as to draw space current and thus have its voltage dependent upon E_{G1} and additionally upon the nature of its output circuit, 25 then the conditions for balance would no longer be the same as those given above, but would, in general, be partially dependent upon the nature of this output circuit. For practical purposes, this would require that the coefficient of 30 coupling between L_2 and L_3 be considerably higher than that otherwise necessary for satisfactory balance. In other words, while g_3 may have some small positive or negative potential with respect to the cathode, it should be sufficiently 35 negative with respect to g_2 and g_4 so that it will not conduct any appreciable space current. Furthermore, under these conditions the element g_3 will serve to prevent the flow of secondary electrons between g_2 and g_4 . 40 In Fig. 3, there are shown several operating curves for the amplifier of Fig. 1, illustrating the transmission characteristics which may be obtained with different degrees of stabilization. In this figure, the abscissa represents the frequency 45 of the wave signal applied to the input, while the ordinate represents the magnitude of the signal which must be applied to the input circuit in order to obtain an output signal of standard amplitude. The curve 1, which it will be noted is 50 symmetrical about the mean frequency F_0 , is that obtained for proper stabilization, that is the stabilization which obtains when the above equation is satisfied. Curve 3 is that obtained in the case where the amplifier is but partially stabilized 55 and where sufficiently high impedance input and output circuits are used so that the amplifier is nearly self-oscillatory. Curve 2 is the type of curve which will be obtained where the amplifier is more stabilized than in the latter case but less 60 stabilized than in the former case. It will be noted that while the amplifier transmission characteristic in this instance is better than curve 3, it is unsymmetrical. A transmission characteristic of the type indicated by curve 1 represents 65 the preferred form. The stage gain has been adjusted to give equal maximum gain in each case.

As is known in the art, in general the gain of an amplifier is proportional, first, to the amplification factor of the tube and, second, to the 70 impedance of the output circuit. It is therefore desirable that a tube having a high amplification factor be used and that the tube be used with high impedance circuits. Where the input and output circuits are in the form of parallel 75 resonant circuits, such as those shown in Fig. 1,

by which a frequency selective amplifier may be obtained, there are two limiting factors in obtaining maximum impedance for the circuit. The first is due to the effect of the tube capacitance or input susceptance. In other words, as the impedance of the tuned circuit is increased, a larger inductance and a smaller capacitance must be used. However, the minimum usable capacitance must be sufficiently large so that variations in the input and output capacity of 10 the tube will not cause appreciable variations in the tuning of the circuit. Another limiting factor is the conductance of the tuned circuit, that is, the resistance due to the wires which form the inductance of the circuit. By minimizing 15 this series resistance and thus the circuit inductance, the impedance of the circuit may be increased, but variations of the conductance or resistive component of the vacuum tube input admittance will have a marked effect upon the 20 transmission characteristics of the stage, unless this equivalent tube conductance is negligible as compared with the actual conductance of the circuit itself. By means of the present invention, the dynamic admittance of the tube is minimized 25 and higher impedance input circuits may be used, first, because the minimum external capacitance which may be used with the input circuit may be reduced, and second, because the effective conductance of the tuned circuit may be reduced. 30 Likewise, the impedance of the output circuit may be increased. As will be apparent, the reactive component of the impedance of the output circuit will be proportional to the impedance of that circuit and therefore, it has been necessary heretofore to limit the impedance of the output circuit, in order to minimize the effect of this circuit upon the dynamic admittance of the tube. However, since the dynamic admittance of the tube is substantially reduced to zero by means of the 35 present invention, considerably higher output impedance circuits may be used and the over-all gain of the amplifier may be increased, and at the same time better transmission characteristics may be obtained. 40

In this connection, it is interesting to note that the use of such high impedance input and output circuits characterized by having a high inductance and a small capacitance, has brought to light a new characteristic of amplifier stages 45 not heretofore known. This phenomenon is observed when the gain of the stage is controlled by variation of the bias on g_1 by means of an automatic volume control (AVC) voltage. It has been found that the static susceptance of 50 the tube will depend in part upon the bias voltage and that the static capacitance of the tube will increase to some extent as the bias voltage is increased. This effect is apparently due to the change in the location of the space charge 55 around the cathode as the grid bias is changed, and it has been found that the use of the high impedance circuits made possible by the present invention enables variation of the tuning of the input circuit over a small range by varying the 60 AVC voltage to thus vary the static admittance of the tube. The net result of this effect is to cause the transmission characteristic of the tube to broaden as the AVC voltage is increased, and thus the gain of the tube is reduced for 65 automatic volume control purposes, while the selectivity of the stage increases as the gain of the stage is increased. As will be apparent, this is a desirable characteristic since, in general, it is desirable that a radio receiver be more selective. 70

tive on weak signals when maximum gain is required than it is on strong signals when a lesser gain is necessary. It is of course not necessary to apply an AVC voltage to g_1 when this phenomenon is not desired.

While the circuit of Fig. 1 shows the use of the invention as applied to an amplifier stage having four fixed tuned circuits and adapted for use in an intermediate frequency amplifier, it will be understood that the invention is not thus limited and that the important elements of the invention comprise the inductance L_2 , the inductance L_3 which is coupled to L_2 , the electrode and wiring capacities C_{14} and C_{34} , and the elements 10 of the tube structure which cause the capacity C_{34} to be considerably larger than the capacity C_{14} . It will be apparent further that the invention is not limited to the illustrated method of obtaining the voltage E_{g3} , since this voltage 15 may be obtained in any desired manner so long as it is properly related in amplitude and phase to E_{g1} . It is believed, however, that the illustrated method of obtaining this voltage is the simplest and most economical method since only a few turns of wire are required.

In one practical embodiment of the invention as shown in Fig. 1, which constituted part of an intermediate frequency amplifier adapted to transmit audio-modulated signals having a carrier frequency of 470 k. c., the impedance of L_1 by itself was about 2500 ohms, while that of each of L_2 , L_4 and L_5 individually was about 5000 ohms (at 470 k. c.). V_1 was a commercial pentode amplifier of the type known as 6K7G, operating with a plate voltage of about 300 volts and a screen voltage of about 100 volts. The primaries and secondaries of T_1 and T_2 were each tuned to 470 k. c. by padding condensers and the coils were slightly less than critically coupled. 20 The "Q" of the primaries and secondaries of each transformer was in the neighborhood of 175. The inductance L_2 was in the form of a bank-wound coil made up of 6 banks totaling 316 turns of Number 7-41 Litzendraht single silk enameled wire, while the tertiary coil L_3 comprised 2 3/4 turns of Number 30 double silk covered wire wound in solenoid form spaced 1/8 of an inch from the secondary, both coils being wound on a 3/4" form. While the proper number of turns for 25 exactly stabilizing the amplifier may be computed from the relation given above, for practical purposes the proper number of turns may be more easily determined by first padding the transformer T_2 to the desired frequency, then replacing the transformer T_2 by a small resistive load and padding the transformer T_1 and finally re-inserting the transformer T_2 and determining if the transformer T_1 is still properly padded. If the stage is properly balanced, it will be found 30 that the transformer is correctly padded. If the additional turns are needed for L_3 to balance the stage, it will be necessary to reduce the capacitance of T_1 to properly pad the circuit. On the other hand, if too many turns have been used, it will be necessary to increase the capacitance of T_1 .

While a single preferred embodiment of the invention has been illustrated for the purpose of disclosure, it will be understood that other forms 35 or embodiments may be employed, and that the invention is capable of modifications such as those herein mentioned.

I claim:

1. An amplifier for wave signals, comprising a 40 space discharge device having an anode, a cath-

ode, a control grid, a screen grid and a third grid, said grids being so positioned with respect to said anode as to provide a certain capacitance between said control grid and said anode and a greater capacitance between said third grid and said anode, an output circuit including an impedance and a source of electrical energy connected to said anode and said cathode, means biasing said screen grid to a positive potential with respect to said cathode, means for supplying an input signal between said cathode and said control grid, and means for applying a signal of opposite phase with respect to said input signal between said cathode and said third grid, and for biasing said third grid so as to prevent it from drawing any substantial space current, the ratio of the amplitude of said first signal to that of said second signal being substantially equal to the ratio of said second capacitance to said first capacitance.

2. An amplifier for wave signals, comprising a space discharge device having an anode, a cathode, a control grid, a screen grid and a third grid, said control grid being adjacent said cathode, said screen grid and said third grid being positioned between said control grid and said anode, thereby providing a capacitance between said control grid and said anode, and a much greater capacitance between said third grid and said anode, an output circuit including an impedance and a source of electrical energy connected to said anode and said cathode, means biasing said screen grid to a positive potential with respect to said cathode, means for supplying an input signal between said cathode and said control grid, and means for applying a signal of opposite phase with respect to said input signal between said cathode and said third grid, and for biasing said third grid so as to prevent it from drawing substantial space current, the ratio of the amplitude of said first signal to that of said second signal being substantially equal to the ratio of said second capacitance to said first capacitance.

3. An amplifier for wave signals, comprising a space discharge device having an anode, a cathode, a control grid, a screen grid and a third grid, said control grid being adjacent said cathode, said screen grid and said third grid being positioned between said control grid and said anode, thereby providing a capacitance between said control grid and said anode and a greater capacitance between said third grid and said anode, an output circuit including an impedance resonant at one frequency and a source of electrical energy connected to said anode and said cathode, means biasing said screen grid to a positive potential with respect to said cathode, means including a resonant circuit tuned to said one frequency and having an inductive element adapted to be energized by a source of input signals for supplying said signals between said cathode and said control grid, and means including a second inductance coupled to said first inductance for applying a signal of opposite phase with respect to said input signal between said cathode and said third grid, and for biasing said third grid so as to prevent it from drawing any substantial space current, the ratio of said first inductance to the mutual inductance between said first and said second inductances being substantially equal to the ratio of said second capacitance to said first capacitance.

4. An amplifier for wave signals, comprising a space discharge device having an anode, a cathode, a control grid, a screen grid and a third

grid, said grids being so positioned with respect to said anode as to provide a certain capacitance between said control grid and said anode and a greater capacitance between said third grid and said anode, an output circuit including an impedance and a source of electrical energy connected to said anode and said cathode, means biasing said screen grid to a positive potential with respect to said cathode, means including an 5 inductance adapted to be energized by a source of input signals for supplying said signals between said cathode and said control grid, a second inductance coupled to said first inductance, and a connection between said third grid and 10 said cathode through said second inductance, for applying a signal of opposite phase with respect to said input signal between said cathode and said third grid, and for providing a low impedance path for unidirectional current, the ratio of the 15 amplitude of said first signal to that of said second signal being of the same order of magnitude as the ratio of said second capacitance to said first capacitance.

5. An amplifier for wave signals, comprising a 20 space discharge device having an anode, a cathode, a control grid, a screen grid and a third 25

grid, said control grid being adjacent said cathode, said screen grid and said third grid being positioned between said control grid and said anode, so as to provide a capacitance between said control grid and said anode and a greater capacitance between said third grid and said anode, an output circuit including a resonant impedance and a source of electrical energy connected to said anode and said cathode, means biasing said screen grid to a positive potential with respect to said cathode, means including an inductance adapted to be energized by a source of input signals for supplying said signals between said cathode and said control grid, a second inductance coupled to said first inductance, and a connection 15 between said third grid and said cathode through said second inductance, for applying a signal of opposite phase with respect to said input signal between said cathode and said third grid, and for providing a low impedance path for unidirectional current, the ratio of the amplitude of said first signal to that of said second signal being of the same order of magnitude as the ratio of said second capacitance to said first capacitance. 20
